UNITED STATES PATENT OFFICE.

ELMER E. KILMER AND IRVING A. KILMER, OF SCHENECTADY, NEW YORK.

WIRE-TWISTING MACHINE.

SPECIFICATION forming part of Letters Patent No. 247,362, dated September 20, 1881.

Application filed April 23, 1881. (No model.)

To all whom it may concern:

Be it known that we, ELMER E. KILMER and IRVING A. KILMER, citizens of the United States, resident at Schenectady, in the county 5 of Schenectady and State of New York, have invented certain new and useful Improvements in Wire-Twisters; and we do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 Figure 1 is a perspective view of the device. Fig. 2 is a vertical transverse section, showing the vise. Figs. 3, 4, 5, and 6 are detail views, showing different parts. Fig. 7 is a side elevation. Fig. 8 is an enlarged detail section, 20 showing the tension-spring on the driving-shaft. Fig. 9 is an enlarged detail perspective of the yoke and the notched driving-wheel.

This invention relates to improvements in 25 machines for twisting wire.

The invention consists in the construction and arrangement of parts hereinafter set forth.

In the annexed drawings, the letter A represents a supporting-frame, having legs $a a'$ and 30 top a^2 , having opening a^3 , and upon the sides of the opening the strips $a^4 a^5$. Secured to these strips on top by its side pieces, $b b'$, is the metallic bed-frame B, the opening b^2 of which is over that of the table A. One end, 35 b^3 , of this frame B rises up above the sides $b b'$, and has the plate C secured to its inner face and vertically adjustable thereon by slots c and set-screws b^4 , which said plate C has the outwardly-projecting flange c' at the top. Rig- 40 idly secured to this plate C, but with a space, c^2 , between, is the fixed jaw D' of a vise, D, the loose jaw D^2 of which is pivoted at d' to the plate C, leaving a space similar to intervening space c^2 , and braced from jaw D' by 45 the tie-plate c^4 . These jaws are provided with the wear-plates $d d^2$, the latter having the groove d^3 , and held adjustably upon the top of plate C by the set-screw c^5 is a support-plate, 50 d^5 , which has a stud, d^6 , extending down into plate C and bound by a screw, c^6 , and which regulates the position of the wire with regard

to the vise. Adjustably secured by an arm, e , under flange c' , to plate C, is a bracket, E, extending out from said plate away from the rear of the table A, and having the returning 55 arm e' , pivoted between the branches of which is the lever F, having its front end, f , hinged and held in alignment by stops f' , the said end having an upward swing and provided with a hook, f^2 . This lever F is loosely held by a bolt, f^3 , in a fork, g , at the upper end of a connecting-rod, G, in another fork, g' , of which is loosely held the end h of a cam, H, having its head h^1 pivoted in a strap, h^2 , which surrounds the jaws of the vise D, and is adjustably held 60 to the fixed jaw D' by slot and screw and by brace h^3 , the position of the strap being regulated by bolt h^4 .

The edge h^5 of cam-head h^1 bears against the loose jaw D^2 , pressure being applied by a 70 treadle, I, through rod G, which causes the head h^1 to force the jaws together and the lever F to come down before the vise. The wire to be bent is in position as the lever F descends, and the latter passes below the wire 75 by means of its hinged head. This strikes the wire and swings back, the joint coming in front of the wire, and after passing the front end falls by gravity into place. A spring, i, returns the treadle, (a stop preventing too much 80 play,) releasing the vise, and the hook f^2 throws the loop off, the lever thus acting as an ejector as the retractile spring h^6 draws back loose jaw D^2 .

In a former patent to us is shown a plate-spring within the vise coming between the jaws, being a pressure-spring, and which from its position may be broken. The spring h^6 , being outside, is in no danger of being crushed, and is therefore an improvement.

Held adjustably by bar k , bolt k' , and a nut upon the top of sides $b b'$, is the carriage K, having the end brackets, $k^2 k^3$, between the top forks, $k^4 k^5$, of which is held the bearings L M, made adjustable by bolts $l m$ and binding-screws $l' m'$. Sleeved through these bearings is the driven shaft N, having at its end opposite the vise the chuck n , in which is secured adjustably a bent rod, n' , and on which is held adjustably another bent rod or wire, n^2 .

Rod n' has the downward and outward bend n^3 , and is furnished with an eye, n^4 , in which

is held a mandrel-post, n^5 , made removable, so that different sizes and shapes may be used, about which post the loop is formed when the wire is twisted, the length of loop being gaged by the distance of the depending end n^6 of wire n^2 from said post, an adjustable eye, n^7 , on this wire n^2 regulating the position of the wire to be twisted up and down on the mandrel-post.

- 10 On the periphery of the chuck n is formed or secured a stud, n^8 , which, engaging a spring-pawl, n^9 , prevents back motion. Keyed to shaft N , about mid-length, is a block, O , between the face o of which and bearing L is a stout spiral spring, l^2 . Surrounding said shaft N , and between its face o' and bearing M , is a tube, P , through which the shaft passes, said tube being loose on the shaft, but held to engagement by a ratchet, p , at its end p' , and a pawl, p^2 , on the face o' of block O . At its other end, next bearing M , this tube P is surrounded by a barrel-spring, Q , held in a guide, q , and secured at one end to the tube, and at its other to the carriage, said spring operating in a direction opposite to that of the ratchet at the other end of the tube P . Secured at one end to tube P , and wrapped about between the ratchet and the spring, is a chain, R .

15 S^2 are two bracket-arms, which spring up from the side b of frame B , having in their bearings $s s'$ a shaft, T , the ends $t^5 t^6$ of which project, one, t^5 , having the spring t^2 to check rotation, the other, t^6 , a crank-arm, t^3 , to the end t^4 of which is adjustably connected the loose end r of chain R . The spring t^2 , being bound between the bracket-arm S and a nut on the end of shaft T by pressure, keeps the shaft from flying back with a jerk.

20 Loosely sleeved upon shaft T is a wheel, t , having in its end toward bracket S the notches t^6 , with abrupt shoulders t^7 , and sloping ones t^8 . Keyed to shaft T , between this wheel t and bracket S , is a case, V , in which is placed parallel to the shaft a spring-actuated bolt, v . This bolt v slides in the case V , the action of the spring v' being to throw it into one of the notches t^6 of wheel t , the said bolt having a finger, v^2 , which projects through a slot, v^3 , in the case.

25 Projecting upward from the side b of frame B , between brackets $S S'$, is another but shorter bracket, W , having two curved arms, $w w'$, arranged in the plane of wheel t , and located at its notched end, said bracket having also on the side away from the wheel the guide-eyes $w' w^2$. Below these guide-eyes, and in line therewith, is a rod, X , having the guide-fork x .

30 Through eyes $w' w^2$ passes a rod, Y , having sleeved thereon, between the eyes, a spring, y , and above this a key, y' , passing through the rod, the spring pressing between eye w' and the key, the latter bearing against eye w^2 . Above eye w^2 this rod Y is provided with a head, y^2 , coming alongside of the arms $w w'$ of bracket W , and having the arm y^3 projecting toward the bed-frame concaved on top, pointed at the end y^4 , and having the beveled-

off surface y^5 , which terminates at a shoulder, y^6 , just beyond the vertical plane of rod Y . Just below the eye w' this rod Y has upon opposite sides the grooves y^7 , the lower end of the rod passing through an eye, z , at the upper end of a connecting-rod, Z . This eye z has a hole, z' , fitting the body of the rod, and a slot, z^2 , fitting the reduced portion at the grooves y^7 . 75

The rod Z is held in the fork x firmly by a spring, z^3 , and has a curve, z^4 , just above the fork, and is operated by a treadle, Z' , returned by a spring, z^5 , and limited by a stop, z^6 . The spring z^3 operates to hold the slotted part of the eye z in engagement with the reduced portion of rod Y , by means of which engagement the rod Y is pulled down when the treadle Z' is depressed until the bend z^4 bears against the fork x and moves the rod Z off, so that 80 the rod Y slides into hole z' , when the compressed spring y throws rod Y up, and the treadle being released, the spring z^5 throws the rod Z up for another stroke.

In operating this machine the wire is bent 90 around the mandrel-post and passed between the jaws of the vise by pressing on treadle I , as before described. Power is applied to wheel t , running loose on shaft T , and to propel the machine the treadle Z' is depressed. 95 This pulls down rod Y until its head comes below the end of finger v^2 on bolt v , when spring v' shoots the bolt toward wheel t , catching in one of the notches t^6 , and bearing against shoulder t^7 , locks the wheel to the shaft and 100 causes the latter to turn.

In case one of the notches t^6 is not in line when the bolt is shot, the base of the arm y^3 is made wide enough to catch the finger v^2 and keep it from dropping back behind shoulder t^7 105 when rod Y comes back, and the bolt is ready for the next notch. As the wheel and shaft now turn, the crank-arm t^3 pulls on the chain R , causing tube P , and through the ratchet-and-pawl connection the shaft N , to 110 turn and twist the loop, at the same time compressing springs Q and l^2 , the former by rotation, the latter by endwise play of shaft N , the latter being pulled by the twisting up of the wire. When the crank reaches the extent 115 of its throw the spring Q , unwinding, turns tube P , the ratchet slipping thereby, winding up chain R , pulling on crank-arm t^3 , which would turn shaft T with a quick jerk, but that the spring t^2 , at the other end of shaft T , checks 120 the action by bearing hard between bracket S and the nut on said shaft. During the rotation, when the end of finger v^2 reaches the bevel y^5 of arm y^3 , passing along this, it draws the bolt v from the notch in wheel t , allowing 125 said wheel to run free and ready for the next loop. During the twisting pressure is kept on treadle I ; but when the loop is made the treadle is released, when the vise opens and the ejector-lever F throws out the loop, as before 130 stated, and spring l^2 throws the shaft back.

If desired, the device may be operated by a treadle, A' , connected to the drive-chain R .

It will be seen that the various parts of the

twisting device proper have been made adjustable, whereby all wear can be compensated for and a true alignment made.

We claim—

- 5 1. The vise D, one of the jaws of which has a groove, d^3 , in combination with the adjustable wire-support d^4 , as set forth.
2. The mandrel-post n^5 , in combination with the adjustable wire n^2 and eye n^7 , as set forth.
- 10 3. Shaft N, tube P, and spring Q, in combination with chain R, crank-arm t^3 , and shaft T, as set forth.
4. Rod Y, having the notches y^7 , in combination with rod Z, having eye z , formed with

hole z' and slot z^2 , and means, substantially as 15 described, for changing the position of the eye z on the rod Y, as set forth.

5. The head y^2 , having the beveled arm y^3 and shoulder y^6 , in combination with the spring-acted bolt v , having finger v^2 , as set forth. 20

In testimony whereof we affix our signatures in presence of two witnesses.
